UNITED STATES PATENT OFFICE.

GEORGE HOLT FRASER, OF BROOKLYN, NEW YORK.

SEPARATOR.

Original application filed August 27, 1914, Serial No. 858,797. Divided and this application filed July 12, 1919. Serial No. 310,328. Renewed November 9, 1923.

To all whom it may concern:

Be it known that I, GEORGE HOLT FRASER, a citizen of the United States, residing at No. 226 Quincy Street, in the borough of Brooklyn, county of Kings, city and State of New York, United States of America, manufacturer, have invented certain new and useful improvements in Separators, being a division of my application Serial Number 858,797, filed August 27, 1914 (renewed December 18, 1918, Serial Number 267,401), of which the following is a specification.

This invention relates to apparatus for separating, sizing, or classifying, collecting or filtering materials by means of a fluid current, and aims to provide certain improvements therein.

Heretofore it has been common to separate fine from coarse material by an air current, by passing the material through a casing in which the current was drawn through the material to float out the fine particles and deposit these in a dust chamber, after which the current was returned and continuously re-used.

With apparatus of this character it has been difficult to prevent coarse particles from being carried out with the fine, and to prevent variations in product due to changing conditions.

This invention relates to apparatus in which a fluid current is utilized to effect separation, and aims to provide improvements whereby one or more products may be separated with greater convenience and certainty than heretofore.

To this end in carrying out the preferred form of the present improvements the material to be treated is formed into a descending blanket, alternately concentrated and expanded as it descends by gravity, intermittently retarded and re-distributed to avoid any undue acceleration, and sufficiently agitated to expose all portions to current action, and while subject to these conditions a fluid current is passed through it to float outwardly from the descending blanket all material capable to floating in the prevailing current. The remaining material descending through the current is withdrawn as tailings.

The extracting process to insure removal

of all fine material involves the risk of carrying out some oversize, and this invention preferably provides for selecting from the extracting current such grade or grades of material as desired and insuring that the final product shall be free from objectionable sizes, and it also provides for more completely collecting the material of the desired fineness and more thoroughly filtering the returned fluid.

The invention further provides for more completely utilizing the space necessarily occupied by the apparatus, for outside current producing provision, for greater accessibility, and for convenience of cleaning, agitation and removal of parts, and it provides various features of improvement, all of which will be hereinafter more fully set forth, and described in detail in their preferred form, with reference to the accompanying drawings, which illustrate the preferred adaptation of my present invention, and in which—

Fig. 1 is a vertical axial section cut approximately on the line 1—1 of Figs. 2 and 3 of an air separator constructed according to the preferred form of my invention, and

Fig. 2 is a horizontal section thereof cut approximately on the planes of the lines 2—2 of Fig. 1, and

Fig. 3 is a horizontal section thereof cut approximately on the planes of the lines 3—3 of Fig. 1.

Referring to the drawings:

Let A indicate the casing, B the driving mechanism, C the feed hopper, D the distributor, E the feed chamber, F the blower, G the dust chamber, H the return passage, I the coarse outlet, and J the fine outlet of an air separator. All of these parts may be of any usual or suitable construction adapted to distribute the material in a descending blanket, cause a fluid current to traverse it, precipitate the fine material floated out by the current continuously re-use the fluid medium, and separately deliver the coarse and fine products.

The casing A shown consists of a cylindrical body *a*, a flat top *b*, a conical bottom *c*, and a separable conical end *d* in which are formed the coarse and fine outlets, and all forming an enclosed chamber in which the fluid is confined.

According to one feature of my invention the driving mechanism comprises a tubular shaft K mounted in upper and lower bearings e in a bracket f mounted on cross-beams g which support the separator. Slidingly or removably keyed or carried on the shaft K is a cone or step wheel h driven from a similar wheel i by a belt j, or other suitable variable speed driving provisions.

10 The shaft K has a shoulder k seating on a split collar l which supports it vertically on a ring, ball or other non-friction annular thrust bearing m, which is centered upon and supported by the lower bearing e. The 15 lower end of the shaft K is reduced so that it can be passed through the vertical bearing and extends into the casing, and has screwed or otherwise separably connected to it a flange o to which the spider p is 20 bolted or otherwise separably connected so as to revolve with the shaft.

The frame f is shown in Fig. 1 as open at its front side so that the shaft may be removed horizontally and then raised vertically, it and the hopper above sliding horizontally into the open side of the frame.

The hopper C is movably and rotatively and adjustably mounted on the frame f and has a tubular extension q telescopically and 30 adjustably entering the feed pipe L, which latter is adjusted vertically by screws r and passes freely through the tubular shaft K opening at its lower end opposite the feed disc s of the distributor from which it can 35 be adjusted to regulate or control the speed of feed. This disc is adjustably and separably connected to the spider p by screws n, and revolves with the shaft K so that material falling on it is thrown out centrifugally and horizontally into the feed chamber.

The distributor D may be any suitable device for feeding the material in a thin blanket or wide thin stream, according to 45 whether the blanket of material to be treated is to descend in a rectilinear or tubular path. It is preferably a driven member, and when the material is to descend by gravity in the form of a tubular blanket 50 the distributor is preferably revolved to throw it outwardly to its path of descent.

I prefer to form the feed chamber E as a circular or annular chamber surrounding the distributor and bordered by a baffle plate 55 shown as a cylindrical ring t against which the material strikes and which is removable for renewal.

Below the baffle ring my invention preferably provides a contracting or feeding ring or plate u, upon which the material falls from the baffle ring and by which it is directed inwardly and delivered onto the first of a series of retarding or distributing rings or members v which check the speed 60 of flow and deflect the material outwardly

allowing it to fall onto a second converging or deflecting ring or plate u down which the material flows and from which it falls onto the next plate v, the contracting and discharging plates or rings being arranged 70 in succession so that the material will flow down one and fall onto the other, be retarded thereby and again fall onto the next, and so on throughout the series of feeding plates whereby the material descending 75 by gravity between them traverses a sinuous path and is alternately retarded and restarted so that undue acceleration of speed of flow is prevented and sufficient agitation is obtained, as the material descends between the plates. When these are arranged in ring form as shown the material descending 80 between them constitutes an endless blanket or tubular envelope between the distributor and the upper cone M below 85 them; and the space between the rings or plates constitutes an annular sinuous separating passage N.

The rings v are relatively short and the rings u are preferably long or upwardly extended to bring their upper edges above the lower edges of the next upper ring v, and preferably to or above the lower edge of the next upper ring u, so that the current 90 in passing between the two rings u must rise 95 as it traverses the passage O and any heavy particles carried out horizontally by it may be dropped onto the upper part of the ring u as the current rises to pass over the top thereof.

For some work where further selection is unnecessary the series of rings u and v only may be used in connection with the current producing and dust collecting provisions, but I prefer to provide for further selecting 100 the material thus separated, and preferably for separately classifying or grading these selections according to their number.

My invention provides for this one or more successive selectors, preferably annular and parallel with the primary feeding and retarding members and concentric with and surrounding these intermediate of the inner and outer chambers. Preferably this is accomplished in the manner shown 110 by interposing a reversely inclined plate or ring w opposite each passage O, which intercepts the outflowing current and deflects it downwardly at an acute angle, and by providing the succeeding annular wall z outwardly of and spaced apart from the adjacent ring w which again intercepts the current and deflects it upwardly, so that the current travels approximately horizontally 115 and preferably slightly upwardly in a sinuous path as it expands outwardly, and large pieces carried by it will be intercepted and fall or be thrown out of it as the current turns around the edges of the rings w in passing these. These rings are spaced apart 120

125

Below the baffle ring my invention preferably provides a contracting or feeding ring or plate u, upon which the material falls from the baffle ring and by which it is directed inwardly and delivered onto the first of a series of retarding or distributing rings or members v which check the speed 60 of flow and deflect the material outwardly

above each passage and inclined downwardly to cause the current to descend between them and are sufficiently spaced apart to give the desired width of passage for the 5 current. Particles deflected downwardly by these rings will descend crossing the current for each succeeding passage so that should any fines be deflected with them the current of a succeeding passage may extract these.

These rings or plates constitute a selector R, and their product may be separately received and withdrawn by a selector cone W, which is preferably accomplished by providing 15 an annular trough or upward passage V around them within the cone or wall z. The current from the several passages O discharges downwardly within this wall z and flows upwardly over the top of the wall 20 and down into the chamber Q. This wall z affords a selector V, the tailings of which may be separately collected as shown by a cone W and passage X and outlet Y when this grade is desired.

25 Proportioning, inclination, relative elevation, and intermediate spacing, of these several parts will be suited to circumstances or requirements, but are preferably such as to effect varying current speeds as well as considerable changes of direction in the current as it progresses outwardly, and in the final 30 selection chamber the area is sufficient to give such volume as will insure a current speed suited to float only particles of the 35 fineness desired in the finest product to be produced so that only this will be carried into the chamber Q and can reach the dust chamber G.

In the chamber Q the current descends 40 with comparative slowness, its floating dust being precipitated by gravity into the settling chamber for removal through the fine outlet.

The air is withdrawn from the chamber Q 45 or returned to the chamber P through the return passage H, which communicates between these and preferably exhausts by suction from the inner side of the chamber Q.

I preferably provide for mechanical extraction or filtration of floating particles 50 from the fluid intermediate of the chamber Q and the return H. I prefer to provide a foraminous or interstitial wall between these through which the current must pass, and this is preferably a double wall or series 55 of hollow troughs or plates disposed with their concave sides facing the chamber Q and their convex sides facing the inlet H and extending downwardly and outwardly 60 from the cone W, constituting the top wall of the return, to the cone a' constituting its bottom wall. These plates b' are staggered in relation and spaced apart so that circuitous passages c' exist between them 65 through which the current may flow while

their hollow faces will provide a space in which particles may settle and descend without danger of being floated by eddies into the return. The open lower ends of the troughs b' discharge into the dust chamber 70 where there is practically no current sufficient to lift their dust. Thus the returning current is sufficiently free from floating back fines to avoid any loss of efficiency on this score, so that the current may be strong 75 enough to extract all the fines without danger of material loss of efficiency, and the selectors may be used to extract large pieces in such a strong current before they reach the dust chamber.

80 Any suitable current producing means and connection may be utilized with those features of my improvements already described, but I prefer to employ an outside blower or one separate from and independent of the feeder, and to drive this and the latter from the same source of power, preferably a motor Z, coupled to the shaft d' of the blower F, which shaft is shown as extended to the pulley i for driving the feeder.

85 The suction and discharge connections between the outside blower and the chambers Q and P may be made in any suitable way, but according to the preferred form of my invention I provide for utilizing centrifugal 90 action to equalize the outflow and inflow of current and avoid undue variations or inequalities thereof, to preserve a uniform suction throughout the exhaust chamber Q. This is preferably accomplished by connecting the suction pipe e' of the fan tangentially with an annular exhaust passage f' 95 outwardly of and surrounding the distributing and contracting inlet g' of the return and communicating with the latter by a 100 reverse passage h' over an intermediate annular dam i', so that the suction current from the trough f' will cause a rapid whirling action in the latter which will prevent excessive withdrawal of air at any one point 105 around the sinuous annular passages communicating between this and the inlet passage H.

110 My invention provides a similar means for utilizing centrifugal force to equalize 115 the blast as the current comes from the blower to the chamber P which is preferably accomplished by connecting the blast pipe j' of the blower tangentially to an annular blast chamber k' in which the blast will 120 whirl and uniformly discharge over the inner wall of the lower cone or receptacle l' and down through the passage m' to the lower open end n' of the upper receptacle or cone M, through which as it rises it will 125 still be subjected to some whirling action which will aid in avoiding excess of current at any one point.

130 In this way an outside blower as distinguished from one enclosed within the casing

and revolving with the distributor may be utilized at a great saving of power and much simplification of construction, and the desired blower and distributor feeds and adjustments may be had independently, and the blower need not be subjected to great wear from direct contact with the material, as it can operate only on the cleanest air.

My invention provides for utilizing much of the space within the bottom cone, which is not all needed for precipitation of dust, and preferably accomplishes this by locating both the annular suction chamber and its communicating passages, and the annular blast chamber and its communicating passages as well as the intermediate selector passage, all within the dust chamber, and the blast chamber within the suction chamber, so that these all are concentrically superposed and compactly nested around the tailings and selector passage, and the blower may be placed where desired and suitably connected with them.

When used as a separate passage the selector passage is preferably disposed between the suction and blast equalizers by a series of cones spaced apart to give the necessary intermediate passage and suitably connected and separated for convenience and manipulation. As shown the lower cone o' , which is held on the cone d , serves as the inner wall of the dust chamber G and connects with the outlet Y and with the selector passage X . Loosely setting on it is a reverse cone p' serving as the top of the latter passage and the inner wall of the suction chamber f' and loosely setting on this is a cone q' constituting one outer wall of the latter, the top wall of which is the cone r' , all of these cones being suitably supported and mounted so that each can be vibrated or lifted and is movable for cleaning.

The inner troughs b' are preferably rigidly connected to the cone W and supported at their lower ends against the cone a' , but the outer row of troughs are movably or elastically connected at their upper end to the cone W as by springs c^2 , which poise them resiliently so that they may quiver in use to clean themselves, and their lower ends bear against the cone c . The cone c is preferably sectionalized by a section f^2 separably connected so that it can be removed to permit removal of the interior cones.

The cone W above the filter troughs covers and seals the upper ends of these and of the spaces between them to resist downward flow of current or leakage of dust vertically of them, and the cone a' crosses the lower ends of the inner troughs and projects across the apertures between the troughs to resist upward flow of current or leakage of material longitudinally of them, but any other suitable means may be used to prevent leak-

age longitudinally of the troughs and to cause the return current to flow through the horizontally extending current passages afforded by the apertures between their faces to travel approximately at right angles to the longitudinal extension of such faces, so that there may be the minimum of disturbance to the current voids or calms formed in front of these faces and they can serve as downward ways affording conduits across and for conducting out of the path of the current intercepted particles and down which intercepted particles can slide without molestation and by which such particles can be safely conducted through the returning current and directed into the dust chamber out of the current zone.

Where advisable the edges of the cones are slightly spaced to permit settling to drift through and where necessary their edges are valved with a flap d^2 or flexible strip to avoid current leakage while permitting gravity flow of precipitated material.

The outer wall of the blast chamber is shown as a cone s' carrying the outlet I and serving as the inner wall of the passage X , and on this cone is mounted the cone t' which serves as the top wall of the blast chamber and isolates it from the passage. The cone M serves as one inner wall of the blast chamber and the reverse cone u' as its bottom wall. While these cones may be fixed together I prefer to loosely and separably suitably connect and support them so that they may be readily vibrated, adjusted or removed. The spacers between them constitute impact or jarring posts or members, by hammering on which percussively they may be vibrated to loosen adhering material. Adjustable and separable screws e^2 under the cones o' and s' support these. Jarring of the parts may be effected in any suitable way, as by occasionally hammering on the screws e^2 , but I prefer to continuously jar the parts as by providing a jarring post s^2 on the cone o' , and a swinging hammer t^2 which swings in the space between this cone and the outer cone f^2 and alternately strikes the post and the outer cone, and which is swung by a rod u^2 projecting into the path of and struck by the swinging knockers v^2 hinged to a revolving part w^2 fixed on the shaft of the blower F as shown in Fig. 1.

My invention provides for accessibility to the several parts of the device by the operator without substantial manipulation, and for this purpose I preferably construct the tailings outlet I with a large tubular passage x' closed by a cover y' by opening which a man can crawl in and pass through the interior of the separator to adjust, repair or clean it. Similarly the suction and blast passages e' and j' are made respectively with a door z' in direct line with them and of sufficient size to permit entrance of the body

so that the operator can crawl in either the suction or exhaust equalizer.

The several upper cones or receptacles are preferably suspended by rods A' from the top b and positioned centrally by divergent bars a² and b² from the side.

In operation the speed of feed entering from the hopper C will be controlled by adjusting the feed pipe L toward the feed disc s or by regulating the speed of the latter by its driving mechanism. The current will be controlled by the speed of the fan or by a butterfly valve B' or otherwise. The removable cone t' will be used if the selector tailings are to be separately withdrawn.

Current rising into the chamber P will flow out between the rings v, traverse the blanket of descending material, extract the fines and float them out through the passages O. The selectors R and V when and if used will make their proper selections and classifications, and the floating fines passing these will descend through the chamber Q and fall into the dust chamber G, the air carrying these being drawn through the filter and clarified on its way to the return passage H. The exhaust through the latter will be uniform. Any sediment settling within the exhaust chamber will leak through the cracks thereof and fall into the dust chamber. The blast by reason of its centrifugal action will exert a uniform pressure as it flows over and under the walls and rises within the cone M and into the chamber P. Any dust settling in the blast passage will leak through into the main tailings outlet. The feed and withdrawal will be constant, and, once adjusted to the work, operation may continue without change regardless of variations in quantity or quality. A sufficient current to insure complete extraction can be used without danger since the selector will eliminate any large particles blown out at the first extraction. Efficiency will be increased by the internal filtration.

The bottom cone d can be uncoupled and removed for entrance or cleaning, and the three adjacent cones can be removed with it through the large opening in the bottom cone c. The section f² of the cone c can be removed and may carry with it all of the cones below the filter tubes.

It will be seen that my invention provides improvements which can be readily and advantageously availed of and it will be understood that the invention is not limited to the particular details of construction, arrangement or combination of parts, set forth as constituting its preferred embodiment since it can be utilized in whole or in part according to such modifications as circumstances or the judgment of those skilled in the art may dictate without departing from the spirit of the invention.

When feed to the hopper C includes mate-

rial too coarse for passing through the separator a scalper C' is used, which according to one feature of my invention is composed of a slotted foraminous plate or screen bent into steps intermediate of the longitudinal extent of its elongated slots, so that the lower bent portion constitutes an outlet for each slot to permit escape of nails or hanging pieces. This is disposed with its long faces or steps at approximately 45 degrees inclination and its intermediate portions at approximately right angles thereto, and mounted in a trough or chute B' of greater inclination than the scalper. My invention provides a dam or retarder D' opposite each step to prevent too rapid flow. The large pieces scalped out of the feed descend past the separator to a spout E'.

The scalper, having slots narrower than the selector outlets, guards these against possible oversize.

What I claim is:

1. In combination, a casing enclosing a chamber, an upper receptacle mounted in said chamber and having upper and lower openings communicating therewith, a lower receptacle having an open upper part affording communication between said chamber and said lower opening, means for supplying material to be separated to said upper receptacle, means for causing a fluid current to flow through said upper receptacle and upper opening into said chamber and return between said receptacles to said lower opening, filtering means within said casing for intercepting particles floating in such current comprising downwardly extending faces in the path of and opposed to such current and affording downward ways for intercepted particles and affording intermediate of such ways apertures affording inwardly extending passages for such current, and means below such passages for resisting upward flow of such current relatively to them.

2. In combination, a casing enclosing a chamber, an upper receptacle mounted in said chamber and having upper and lower openings communicating therewith, a lower receptacle having an open upper part affording communication between said chamber and said lower opening, means for supplying material to be separated to said upper receptacle, means for causing a fluid current to flow through said upper receptacle and upper opening into said chamber and return between said receptacles to said lower opening, filtering means within said casing for intercepting particles floating in such current comprising downwardly extending faces in the path of and opposed to such current and affording downward ways for intercepted particles and affording intermediate of such ways apertures affording inwardly extending passages for such current,

and means above said faces and covering said passages for resisting flow of such current vertically relatively to them.

3. In combination, a casing enclosing a chamber, an upper receptacle mounted in said chamber and having upper and lower openings communicating therewith, a lower receptacle having an open upper part affording communication between said chamber and said lower opening, means for supplying material to be separated to said upper receptacle, means for causing a fluid current to flow through said upper receptacle and upper opening into said chamber and return between said receptacles to said lower opening, filtering means in said casing for intercepting particles floating in such current comprising downwardly extending faces in the path of and opposed to such current and affording downward ways for intercepted particles and affording intermediate of such faces apertures affording inwardly extending passages for such current, and means below such faces for resisting vertical flow of such current relatively to them.

4. In combination, a casing enclosing a chamber, an upper receptacle mounted in said chamber and having upper and lower openings communicating therewith, a lower receptacle having an open upper part affording communication between said chamber and said lower opening, means for supplying material to be separated to said upper receptacle, means for causing a fluid current to flow through said upper receptacle and upper opening into said chamber and return between said receptacles to said lower opening, filtering means within said casing for intercepting particles floating in such current comprising downwardly extending spaced members affording faces in the path of and opposed to such current and affording downward ways for intercepted particles and affording intermediate of such ways apertures affording horizontally extending passages for such current, and means covering the end of said members for resisting flow of such current vertically relatively thereto.

5. In combination, a casing enclosing a chamber, an upper receptacle mounted in said chamber and having upper and lower openings communicating therewith, a lower receptacle having an open upper part affording communication between said chamber and said lower opening, means for supplying material to be separated to said upper receptacle, means for causing a fluid current to flow through said upper receptacle and upper opening into said chamber and return between said receptacles to said lower opening, filtering means within said casing for intercepting particles floating in such current comprising downwardly extending faces in the path of and opposed

to such current and affording intermediate of such faces apertures affording inwardly extending passages for such current, and springs sustaining said filtering means.

6. In combination, a casing enclosing a chamber, an upper receptacle mounted in said chamber and having upper and lower openings communicating therewith, a lower receptacle having an open upper part affording communication between said chamber and said lower opening, means for supplying material to be separated to said upper receptacle, means for causing a fluid current to flow through said upper receptacle and upper opening into said chamber and return between said receptacles to said lower opening, foraminous filtering means within said casing for intercepting particles floating in such current comprising downwardly extending faces in and across the path of and opposed to such current and affording intermediate of such faces apertures affording inwardly extending passages for such current, and means above said filtering means for preventing leakage of such particles inwardly of said filtering means.

7. In combination, a casing enclosing a chamber, an upper receptacle mounted in said chamber and having upper and lower openings communicating therewith, a lower receptacle having an open upper part affording communication between said chamber and said lower opening, means for supplying material to be separated to said upper receptacle, means for causing a fluid current to flow through said upper receptacle and upper opening into said chamber and return between said receptacles to said lower opening, filtering means within said casing for intercepting particles floating in such current comprising downwardly extending faces in and across the path of and opposed to such current and affording intermediate of such faces apertures affording inwardly extending passages for such current, and means above said apertures for preventing downward leak of such particles intermediate of said faces.

8. In combination, a casing enclosing a chamber, an upper receptacle mounted in said chamber and having upper and lower openings communicating therewith, a lower receptacle having an open upper part affording communication between said chamber and said lower opening, means for supplying material to be separated to said upper receptacle, means for causing a fluid current to flow through said upper receptacle and upper opening into said chamber and return between said receptacles to said lower opening, filtering means within said casing for intercepting particles floating in such current comprising spaced downwardly extending faces in the path of and opposed to such current and affording intermediate of

- their edges apertures affording inwardly extending passages for such current, and means above said passages for preventing downward leakage of such particles through the 5 spaces between said faces.
9. In combination, a casing enclosing a chamber, an upper receptacle mounted in said chamber and having upper and lower openings communicating therewith, a lower 10 receptacle having an open upper part affording communication between said chamber and said lower opening, means for supplying material to be separated to said upper receptacle, means for causing a fluid 15 current to flow through said upper receptacle and upper opening into said chamber and return between said receptacles to said lower opening, filtering means within said casing for intercepting particles floating in 20 such current comprising successive rows of spaced members affording downwardly extending faces in the path of and opposed to such current and affording intermediate 25 of such faces apertures affording inwardly extending passages for such current, and means between said faces for preventing downward leakage of such particles between said faces.
10. In combination, a casing enclosing a
- chamber, a receptacle in said chamber having upper and lower openings communicating with said chamber, means for passing pulverulent material to be separated into said receptacle, means affording a way 30 through said receptacle for the heavier particles of such material, means affording an endless current passage through and around said receptacle, means for circulating a fluid medium through said passage to carry off into said chamber the lighter particles of 35 such material, substantially vertically disposed foraminous filtering means across said passage for intercepting particles carried by such medium, said filtering means being constructed and arranged to conduct the intercepted particles across and below the path of the medium and affording horizontally 40 extending current passages for such medium, and means for jarring said filtering means. 45
- In witness whereof, I have hereunto signed my name in the presence of two subscribing witnesses.

GEORGE HOLT FRASER.
